Primary Examiner — David G Muller*Assistant Examiner* — Nathan M Johnston(74) *Attorney, Agent, or Firm* — Walter A. Rodgers(57) **CLAIM**

The ornamental design for a multi-position plant hanger, as shown and described.

DESCRIPTION

FIG. 1 is a perspective view of a multi-position plant hanger showing my new design;

FIG. 2 is a front elevation thereof;

FIG. 3 is a top plan view thereof;

FIG. 4 is a bottom plan view thereof;

FIG. 5 is a left-side elevation thereof, the right side being the same in appearance;

FIG. 6 is a rear elevation thereof;

FIG. 7 is a perspective view showing the plant hanger rotated 90° from that shown in FIG. 1; and,

FIG. 8 is top plan view of the hanger shown in FIG. 7.

The dotted lines are included for the purpose of illustration and form no part of the claimed design.

1 Claim, 8 Drawing Sheets(56)
